UNITED STATES PATENT OFFICE.

JOHN RILEY, OF MINNEAPOLIS, MINNESOTA.

GANG-PLANK.

SPECIFICATION forming part of Letters Patent No. 733,598, dated July 14, 1903.

Application filed March 17, 1903. Serial No. 148,157. (No model.)

To all whom it may concern:

Be it known that I, JOHN RILEY, of Minneapolis, county of Hennepin, State of Minnesota, have invented certain new and useful

5 Improvements in Gang-Planks, of which the following is a specification.

This invention relates to devices used for loading and unloading merchandise, and the object of the invention is to provide a gang-
10 plank particularly adapted for use around railroad depots or steamboat wharves which will automatically lock itself in position to prevent either end from becoming accidentally displaced or slipping off the car, platform, dray, or other support whereon the plank may be placed and used during the loading or unloading operation.

The invention consists generally in various constructions and combinations, all as hereinafter described, and particularly pointed out in the claims.

In the accompanying drawings, forming part of this specification, Figure 1 is a plan view of the under side of a gang-plank embodying my invention. Fig. 2 is a top view of the same. Fig. 3 is a section on the line *xx* of Fig. 4, and Fig. 4 is a section on the line *yy* of Fig. 3.

In the drawings, 2 represents a plate forming the main portion of the gang-plank and composed in this case of metal; but wood or any other suitable material may be used, if preferred. I have shown the plate provided with downwardly-turned edges and tapered ends for convenience in handling freight thereon, and in case the plank is made of wood its ends will be suitably ironed to brace and strengthen the same. Along the under side of the plate, near the edges thereof, I provide 25 **Z**-bars 3 and 4, arranged in pairs and forming guides for **T**-shaped plate members 5, that are slidable between the same.

6 is a bar loosely mounted in said plates 5 and adapted to slide therewith and whereto 30 an angle-bar 6', having flanges 7 and 8, is secured. The flange 8 is wider than the flange 7, so that when the plank is in position for use the weight of the flange 8 will cause the bar to swing on its pivots and move the flange 50 7 toward the **Z**-bars. This flange 7 has an edge 9, that is turned substantially at right

angles to the flange and adapted to enter notches 10 in the bars 4, and thereby lock the angle-bar and the guide-plates 5 against further movement in either direction. 55

11 is an angle-bar secured to the plate 2, near one end thereof, and having one flange projecting substantially at right-angles to said plate and forming a fixed stop to bear upon the bottom of the car or the edge of the platform or other support upon which that end of the plank rests. The flanges 7 and 8, forming the adjustable stop, are moved along in the guideways until the flange 8 engages the support upon which the other end of the plate 2 is placed, and when in that position the edge 9 will enter the notches 10 at that point and lock the adjustable stop against further movement. The freight-handlers can then move merchandise back and forth over the gang-plank from the car to the platform, or vice versa, without danger of either end of the plank slipping off from the support on which it is placed. In this way damage to merchandise and injury to the men handling the same is 70 avoided. The **Z**-bars, in addition to forming guides for the adjustable stop, also serve to brace and strengthen the plate 2 and render it capable of sustaining the weight of heavy packages of merchandise that are moved back and forth over the same. If desired, an intermediate bar may be placed on the bottom of the plate 2 between the **Z**-bars, and in various other ways the plate may be braced and strengthened to adapt it for the various uses 75 and to the severe strains to which it may be subjected. 80

I claim as my invention—

1. The combination, with a plate, of a fixed stop provided near one end of the same and 90 adapted to engage the floor of a car or the edge of a platform or other support, and an adjustable stop provided on the under side of said plate and arranged to engage the support on which the other end of said plate is placed. 95

2. The combination, with a plate, of a fixed stop provided on the under side thereof near one end, **Z**-bars arranged in pairs and extending lengthwise of said plate on the under side, plates slidably arranged between said bars, said bars provided with a series of 100

- notches, and an adjustable stop carried by said plates and arranged to engage said notches.
3. A gang-plank, comprising a plate having a fixed stop near one end on the under side, **Z**-bars secured to the under side of said plate and near the edges thereof and arranged in pairs, plates slidably supported between the bars of said pairs, a rod carried by said plates and an angle-bar mounted on said rod, one flange of said bar being wider than the other and the narrower flange having a bent edge to enter said notches.
4. A gang-plank, comprising a plate having a fixed angle-bar stop near one end on the under side, **Z**-bars arranged in pairs on the under side of said plate and extending longitudinally thereof and bracing and strengthening the same, said pairs of **Z**-bars forming guideways, and the inner bar of each pair provided with a series of notches and an adjustable stop supported by and slidably in said guideways and having means for engag-
- ing said notches to lock said stop against movement in either direction. 25
5. A gang-plank, comprising a metallic plate having a fixed stop near one end on the under side, guideways provided on the under side of said plate and extending lengthwise thereof, a stop slidably mounted in said ways, and means for locking said stop. 30
6. A gang-plank, comprising a metallic plate having a fixed stop near one end on the under side, **Z**-bars arranged in pairs on the under side of said plate and extending lengthwise thereof and forming guideways, and an angle-bar stop slidably mounted in said guideways and arranged to automatically engage notches provided in said **Z**-bars, for the purpose specified. 35
- In witness whereof I have hereunto set my hand this 13th day of March, 1903.
- JOHN RILEY.

In presence of—
RICHARD PAUL,
S. V. GRIFFIN.
